Patented Mar. 15, 1921.

UNITED STATES PATENT OFFICE.

WILLIAM M. ANGUS, OF DENNISON, TEXAS.

SAFETY-CASING CLAMP.

1,371,835.

Specification of Letters Patent. Patented Mar. 15, 1921.

Application filed October 7, 1920. Serial No. 415,341.

To all whom it may concern:

Be it known that I, WILLIAM M. ANGUS, a citizen of the United States, residing at Dennison, in the county of Grayson and 5 State of Texas, have invented certain new and useful Improvements in Safety-Casing Clamps, of which the following is a specification.

My invention relates to equipment for 10 drilling and operating oil and gas wells and other deep wells, where two or more casings of different sizes are used either during the operation of drilling, or afterward, or both. In drilling such deep wells, it is the practice 15 to insert in the hole a large casing to a depth depending on local conditions, and then a casing of smaller diameter inside the larger casing to a greater depth, and so on until the drill rests on the sand and is drilled into the 20 sand. The casing of smallest diameter usually has an uncertain foundation or support, and is liable to slip or drop or settle, and clog the well, or render the repair thereof very expensive and often impossible. 25 The outer casings usually have a solid foundation or support by reason of resting in or upon the intermediate solid rock or shale. If a flowing well is obtained, the outer casings are withdrawn, or pulled, leaving only 30 the smallest and the next to the smallest for lateral support for the walls. Although the method of operations differs greatly in different circumstances, depending on local conditions, supplies, local practices, etc., 35 there is always present the danger of losing the casing last inserted in the well.

It is the object of my invention to provide 40 a strong, simple, durable, and efficient clamp which is applied to the upper end of an inner casing and which supports that inner casing upon the upper end of the next outer casing even while the still larger casings are being pulled; and it is the further object to provide the parts, improvements and 45 combinations in a safety casing clamp hereinafter set forth and claimed.

In the drawings accompanying and forming 50 part of this specification and in the description of the drawings, I have shown my invention in its preferred form and what I deem to be the best mode of applying the principles thereof; and it is to be understood that, within the scope of the appended claims, I contemplate changes in form, 55 portions and materials, the transposition

of parts, and the substitution of equivalent members, without departing from the spirit of my invention.

Figure 1 is a plan view of a safety casing clamp made in accordance with the principles of my invention, the full outlines showing the clamp closed, and the dotted outlines showing the clamp opened on its hinge. Fig. 2 is a view of one of the two pins, they being alike. Fig. 3 is a side elevation of the clamp. Fig. 4 is a vertical central sectional elevation approximately on a plane indicated by the line 4—4 in Fig. 1. Fig. 5 is a vertical central sectional elevation of the clamp approximately on a plane indicated by the line 5—5 in Fig. 1, with those portions of the two casings to which the clamp is applied; this view also showing a portion of the next outer casing.

Similar reference characters indicate 75 similar parts throughout the several drawings.

The clamp is composed of two semi-cylindrical members 6 and 7, hinged together so as to form a collar. The member 6 is formed 80 with a tongue 8 between the two offsets 9 and with the two lugs 10, 10; while the member 7 is formed with the lugs 11, 11 and the tongue 12. These tongues and lugs engage with each other and have holes 13 85 through them, through which are passed the pins 14, 14, the one forming a hinge and the other forming a lock. The upper end of each pin is bent at a right angle, as shown at 15 and rests in the notch 16 formed in the 90 lug. The lower outer corner of the clamp is rabbed, as shown at 17, for a purpose hereinafter explained. The extreme ends of the tongue and lugs forming the hinge are rounded, as indicated at 18, to permit proper 95 action of the clamp members on the hinge.

The object in making the clamp in two parts, is to adapt it to be slipped onto the casing laterally; and it is made to fit around the casing to which it is applied closely. It 100 is applied thereto by removing the pin 14 opposite the hinge, opening the members on their hinge, slipping the members from the side over the casing, closing the members, and inserting the pin; and it is removed by 105 the reverse operation. The recess 16 permits the bent-over head of the pin to be confined within the limits of the body of the collar without projecting therefrom, and the head formed as shown affords a means 110

for prying the pin out after the same has been permitted to get rusty or has otherwise become tight in its seat.

Referring to Fig. 5, which shows the use 5 of the clamp; 20 is the innermost casing, to which the clamp is applied with the coupling 21 resting on the upper edge of the clamp and forming the support upon the clamp for the casing represented by the upper end 20. 22 shows the upper end of the 10 next outer casing. The lower end of the clamp rests on the upper end of this casing and has its support thereon, with the rabbet 17 engaging the upper end of the coupling 23. 24 represents a next outer casing being 15 pulled out of the well without interfering with the support of the innermost casing upon its next adjacent outer casing.

It is contemplated that the clamp may be 20 used for supporting any inner casing upon any outer casing, regardless of size, although it will be found particularly useful in the support of the innermost casing upon the next outer casing, both during the sinking 25 of the former and while pulling the

larger casings as the said next casing; and as well, it will be useful as a permanent safety element in supporting the innermost casing if a permanent well is obtained.

The clamp is to be made of metal, preferably cast steel.

Having thus described my invention, what I claim is:

1. A safety casing clamp comprising a collar consisting of two semi-cylindrical halves hinged together at one contacting end and means for interlocking said halves at the other end, said collar being formed around its lower outer edge with a rabbet. 35

2. A safety casing clamp consisting of the combination of two semi-cylindrical members hinged together at one side and formed with interlocking lugs at the other side, and a pin extending removably through said lugs, said pin having a bent-over upper end 40 and the upper lug having a recess for the reception of said bent-over end, and the lower outer edge of said members being rabbed. 45

WILLIAM M. ANGUS.
